(57) **CLAIM**

(21) Appl. No.: **29/296,582**

The ornamental design for an exterior housing for a shower drain pump, as shown and described.

(30) **Foreign Application Priority Data**

Apr. 28, 2007 (EM) 000717541

DESCRIPTION

(51) **LOC (9) Cl.** **15-02**

FIG. 1 is a perspective view of an exterior housing for a shower drain pump showing our new design;

(52) **U.S. Cl.** **D15/7**

FIG. 2 is left side elevational view, the right side view being a mirror image;

(58) **Field of Classification Search** D15/7-9;

FIG. 3 is a front elevational view; and,

D23/231, 232-225; 417/410.1, 359, 415-416,
417/234, 321, 265, 405

FIG. 4 is a bottom plan view.

See application file for complete search history.

The broken line representations are for illustrative purposes only and form no part of the claimed design.
